Claims priority, application Austria Jan. 18, 1958

6 Claims. (Cl. 51—206)

The present invention is concerned with the problem of providing a grinding wheel or more generally speaking a rotary abrasive member having a large working width. It is known that it is not possible simply to increase the working width of a rotary abrasive member by forming said member to have an appropriate width, extending, as it were, a grinding wheel to form a grinding cylinder. This does not enable the actual utilization of the entire width of the abrasive member for machining. For instance, a grinding wheel having a width of 40-60 mm. machines only with one fourth or one fifth of said width. This means that the work performed by the grinding wheel is done by a fraction of the periphery of the wheel, namely, by that portion which is in front when viewed in the feeding direction. Under these circumstances it is advisable to avoid grinding wheels having an uneconomical width and to use narrow grinding wheels separated by free spaces.

It is known to cause several grinding wheels held spaced by insert rings to act on the workpiece at the same time. Abrasive segments are also known which are combined to form one or several abrasive rings acting on the workpiece.

These proposals are unsatisfactory because several wheels each of which functions satisfactory in itself will work satisfactorily when combined only if their diameters are appropriately selected. As even the slightest differences in composition, which are due to the manufacture of the wheels, cause a differential wear of the grinding wheels, it is not or hardly possible in practice to maintain this relation of the diameters. For this reason the usefulness of such sets of grinding wheels is highly problematical.

It has also been proposed to align several spaced grinding wheels on a shaft and to set the wheels at an angle to the shaft like wobble plates, having a more or less elliptical periphery, depending on their inclination. As a result, the working surface of the abrasive member has an effective width which is a fraction of the working width required for the abrasive member. The rotation of the abrasive member causes its grinding face to travel axially along the workpiece. This construction is unsatisfactory because the use of elliptical abrasive members is unsatisfactory in itself and because such abrasive members when combined have rotary balance only if their major and minor axes, respectively, lie exactly in common planes. This requires an exact alignment of the grinding wheels on the spindle, which alignment is difficult to achieve and maintain.

The present invention proceeds on a different course. It provides a rotary abrasive member for use like a grinding wheel, which member is composed of a plurality of axially aligned, hard components and the working face of which has an acting width which is a fraction of the working width required for the abrasive member, the lateral boundary faces of the components being inclined with respect to the axis of rotation of the abrasive member so that a rotation of the abrasive member will cause

2

the abrading face thereof to travel axially over the workpiece, and is characterized in that the components complement to form a helical body, the axial cross-section of which decreases from the inside towards the outside.

5 Each component preferably forms only a sector-shaped part of the helical body i.e. the peripheral length of each component is less than 360 degrees, and adjacent components form staggered joints.

Thus, this does not concern an arrangement of several 10 separate grinding wheels one beside the other, which wheels cover the entire working width only as a result of a feed movement imparted to them, but a functional unit, which provides the working width by a special configuration of the working face of the abrasive member although this does not preclude the additional use of a feed movement. Whereas the components are also inclined with respect to the axis they are not confined by ellipses but have circular outer boundary edges.

It will be appreciated that an abrasive member according to the invention having a working surface in the 20 form of a helical strip will produce an uninterrupted ground surface and grinding marks cannot occur. Using discs having each a width of 3-20 mm. it is thus possible to obtain a multiple-turn helical member having a 25 grinding width of 6-60 mm. and more without feed movement. If an inclined grinding wheel element has at its periphery an acting width of, e.g., 4 mm., the 30 inclination or helical configuration may be such as to give that element a working width of about 5-10 mm. Thus, the performance of the wheel element is greatly increased beyond its actual grinding width whereas the generation of heat and the power requirement are reduced owing to the reduced thickness. This disc can also be cooled 35 more satisfactorily.

It has been found suitable for the components assembled to form the helical body to have a high strength and a substantial elasticity. In this connection it is sufficient, however, to use those compositions known for 40 abrasive members which have a relatively high strength and elasticity owing to the use of high-grade bonding materials and may be improved by an admixture of fiber materials. A person skilled in the art will be aware of such compositions for abrasive members and they need not be discussed here more fully. Besides, the cross-sectional shape of the components according to the invention also contributes to the strength thereof, the rotating mass decreasing from the inside to the outside according to a linear or non-linear function. The reduction in cross-section from the center to the periphery 45 should not be less than would result from a taper of 1:10.

The invention is illustrated in the accompanying drawing, in which

55 Fig. 1 is an end view showing an abrasive component for an abrasive member according to the invention.

Fig. 2 is a sectional view taken on line II—II of Fig. 1.

Fig. 3 is a partly sectional view showing an abrasive member according to the invention, mounted on a grinding spindle.

60 Fig. 4 shows as a detail of the construction of Fig. 3, the joint between adjacent abrasive components.

Near the rim 2 of its center hole the sector shaped helical abrasive component 1 has in its helical side faces 65 axially extending concentric flanges 3, which serve for effectively anchoring a series of such components in the complementary circular recesses of carrying rings 4, Fig. 3. These carrying rings consist of ring sectors which complement to form a helical body carried by the shaft 5 and having the same lead as the helical abrasive member 70 formed by the components 1. The helical member consisting of the ring sectors 4 is non-displaceably gripped

by nuts 6 and a bearing flange 7 on the shaft 5, which has screw-threaded extensions 8 for this purpose.

It is apparent from Fig. 4 that the joint between one component 1a to the next 1b may be offset. Fig. 4 is a top plan view showing the joint between two adjacent components. Each radial boundary face 9a and 9b of each component has a continuous offset so that interengaging steps are formed at the radial boundary face of adjacent components. The axial spacing of the components may also be such that the beginning of one component is axially spaced from the end of the preceding component. This will result in an abrasive member formed like winding stairs. It will be understood that these are only details of construction and other fixations and configurations may also be adopted.

The abrasive member having according to the invention the form of a helical body (helical surface or winding stairs) has a grinding performance similar to that of a plurality of narrow grinding wheels and enables the same or an increased removal of material with an abrasive member having a much lower weight; it is free of the above-mentioned disadvantages of a plurality of circular or elliptical individual discs aligned parallel to each other on a shaft. The abrasive member according to the invention has also the advantage that components of different grain size and even of different diameter may be carried on a single shaft. The (helical) space between the components ensures an effective discharge of the abrasive dust. Each component does not only grind at its end but also with its side owing to the helical movement of the same.

What is claimed is:

1. A rotary grinding member, comprising a shaft having an axis; a plurality of abrasive components mounted on said shaft, each one of said components having two radially extending side faces spacedly facing corresponding side faces of another component in an axial direction, a grinding face connecting said side faces, the grinding faces of said components defining a surface of revolution about said axis, and two radially extending bounding faces, each of said bounding faces connecting the two side faces of said one component and extending radially from said grinding face thereof, said two bounding faces

being angularly and axially offset from each other, said grinding face extending helically between said bounding faces, each bounding face of said one component being positioned for abutting engagement with a corresponding bounding face of an adjacent component, whereby the grinding faces of the two adjacent members form a joint, said grinding faces at said joint having respective portions which overlap in an axial and in a circumferential direction; and fastening means for securing said components to said shaft.

2. A grinding member as set forth in claim 1, said two bounding faces being offset angularly by an angle of more than 180° and substantially less than 360°.

3. A grinding member as set forth in claim 2, wherein at least one of said side faces is formed with an axial projection of arcuate shape about said axis, and said fastening means includes a ring member interposed between said one side face and the facing side face of another component, said ring member being formed with a recess matingly engaging said projection, and means for securing said ring member on said shaft.

4. A grinding member as set forth in claim 1, said two side faces of each component converging axially in a radially outward direction.

5. A grinding member as set forth in claim 1, wherein each boundary face has a radially extending offset matingly engaging a corresponding offset on the corresponding boundary face of the adjacent member, whereby the joint formed by the grinding faces of the two adjacent members has a step-like shape in said surface of revolution.

6. A grinding member as set forth in claim 1, wherein said surface of revolution is a cylinder.
